UNITED STATES PATENT OFFICE.

MARION H. CAZIER, OF CHICAGO, ILLINOIS.

DESIGN FOR A TROUSERS-HANGER.

SPECIFICATION forming part of Design No. 34,023, dated February 5, 1901.

Application filed April 16, 1900. Serial No. 13,148. Term of patent 14 years.

To all whom it may concern:

Be it known that I, MARION H. CAZIER, a citizen of the United States, residing at Chicago, in the county of Cook and State of Illinois, have invented and produced a new and original Design for Trouzers - Hangers, of which the following is a specification, reference being had to the accompanying drawings, forming a part thereof.

Figure 1 is a side view of a trousers-hanger, showing my new design therefor. Fig. 2 is another view of the same looked at from below. Fig. 3 shows an end view of the same.

As shown in the drawings, the leading features of my design consist of the two similarly-formed clamping-jaws A and the V-shaped suspending-spring B, to the extremities of which the jaws A are rigidly attached.

The jaws A are centrally arched, as shown at 20 a, for a portion of their length, the arched

portion being carried backwardly from the inwardly-facing portions a'.

The essential features of the design are found in a pair of centrally-arched and similarly-formed clamping-jaws, which are severally and rigidly applied to the extremities of a V-shaped connecting portion. 25

Having described my invention, what I claim as new, and desire to secure by Letters Patent, is—

The design for a trousers-hanger as herein shown and described.

In testimony whereof I have signed my name in the presence of two subscribing witnesses.

MARION H. CAZIER.
